UNITED STATES PATENT OFFICE.

JAMES E. WEAVER, OF ALLEGHENY, PENNSYLVANIA.

EVAPORATING-PAN.

SPECIFICATION forming part of Letters Patent No. 241,258, dated May 10, 1881.

Application filed May 8, 1880. (No model.)

To all whom it may concern:

Be it known that I, JAMES E. WEAVER, of Allegheny, in the county of Allegheny and State of Pennsylvania, have invented a new and useful Improvement in Evaporating-Pans; and I do hereby declare that the following is a full and exact description thereof, reference being had to the accompanying drawings, and to the letters of reference marked thereon.

10 My invention relates to an improvement in evaporating-pans; and it consists in the peculiar construction hereinafter described.

To enable others skilled in the art with which my invention is most nearly connected to make and use it, I will proceed to describe its construction and operation.

In the accompanying drawings, which form part of my specification, Figure 1 is a perspective view of my improvement in evaporating-pans. Fig. 2 is a vertical and longitudinal section of the same at line *x* of Fig. 1. Fig. 3 is a vertical and transverse section of the same at line *y* of Fig. 1. Fig. 4 is a transverse section of the same when constructed without a top—that is to say, when it is an open pan. Fig. 5 is a longitudinal section of the same when constructed without a top—in other words, when when it is an open pan. Fig. 6 is an enlarged view of a section of my improvement.

30 The evaporating-pan represented in the accompanying drawings is provided with an evaporating-chamber, *A*, and steam-chamber *B*. The partition-plate *C* forms the bottom of the evaporating-chamber *A* and top of the steam-chamber *B*. The bottom *D*, top *E*, and partition *C* are each furnished with a flange, *f*, which is riveted to the sides *G*. The flange *f* of the partition *C* should be in depth more than the intended depth of the liquor flowing through 40 the chamber *A*. Vertically through the chambers *A* *B* pass three hollow rivets, the ends of which are upset similar to the upsetting of the ends of the tubes in the construction of tubular boilers.

45 In supporting the pan over its furnace supporting-rods are passed up through the bore of the rivets *H* and attached to supporting-timbers.

In constructing the pan, the bottom *D*, top *E*, and partition *C* are placed on top of each

other and clamped firmly together. The openings for the stay-bolts *i* and *j* are then drilled or punched through the three so that they will be in line with each other, so as to properly receive said stay-bolts. These openings are 55 then "tapped"—that is, furnished with screw-threads corresponding to the screw-threads on the stay-bolts *i* and *j*—care being taken to make a tight fit of said bolts in said openings—that is to say, said bolts should fit said openings so 60 neatly as to require considerable force to screw them into said openings. The flanges *f* being formed, and the necessary openings made in them and the sides *G* for the rivets, the bottom *D* is then riveted to the sides *G* and the edge 65 of the flange *f*, and the lower edge of the sides *G* are chipped and calked. The partition *C* is then riveted to the sides *G*, and its flange *f* chipped and calked. The bolts *i* are then 70 screwed into their openings in the partition *C* and bottom *D*, and riveted or upset, as indicated at *K*. The top *E* is then placed in position and riveted to the sides *G*, and the top edges of the sides and flange chipped and calked. The bolts *j* are then screwed in their 75 openings in the top *E*, partition *C*, and bottom *D*, and their ends riveted or upset, as shown at *l* in Fig. 6.

In some cases the evaporating-pan is constructed without the top *E*, forming what is 80 known as an "open" evaporating-pan, a transverse section and longitudinal section of which are shown in Figs. 4 and 5, but in all other respects is the same in construction as the evaporating-pan represented in Figs. 1, 2, 3, and 6. 85

In the construction of the evaporating-pan hereinbefore described about two of the bolts *i* are used to one of the bolts *j*, for the reason that the steam-chamber *B* is subjected to the greater pressure. The great number of screw 90 stay-bolts used adds greatly to the strength of the pan and also to its efficiency in evaporating, for they take up the heat from the steam and transmit it to the partition *C*, over which flows the liquor to be evaporated.

95 By making the flange *f* of the partition *C* of greater depth vertically than the depth of the liquor flowing over its surface the liability to leakage at the calked seam of the flange is obviated.

The chambers A and B are furnished with suitable inlet and outlet openings, the arrangement of which I leave to the skill of the art.

Having thus described my improvement, what I claim is—

1. The herein-described evaporating-pan, composed of the bottom and top D E and intermediate partition C, forming chambers A D, screw-bolts *i* and *j*, having screw-threads extending their entire lengths, and hollow bolts

or rivets H, for the reception of supporting rods, as and for the purpose specified.

2. An evaporating-pan having chambers A and B, with the flange *f* of the partition C, substantially as herein described, and for the purpose set forth. 15

JAS. E. WEAVER.
